UNITED STATES PATENT OFFICE

JAMES B. PHILLIPS, OF PORTLAND, MAINE.

COAL HANDLING AND STORING APPARATUS.

1,216,603.

Specification of Letters Patent.

Patented Feb. 20, 1917.

Application filed May 21, 1914. Serial No. 839,931.

To all whom it may concern:

Be it known that I, JAMES B. PHILLIPS, of Portland, in the county of Cumberland and State of Maine, have invented certain new and useful Improvements in Coal Handling and Storing Apparatus, of which the following is a specification.

My invention relates to an apparatus adapted to be used for the handling and storing of coal, ore or other like material.

Coal is commonly stored in large piles or heaps by means of an elevated bridge located high enough to extend over the heap. The bridge is provided with a traveler by 15 which the coal is carried in buckets and dropped on the heap.

This method of storing coal while it enables large quantities to be stored in open spaces requires an expensive apparatus and 20 is not adapted to storing medium amounts on account of the expense.

The object of my invention is to provide an apparatus which may be used for discharging coal from vessels and either storing it in heaps or loading it at once into cars or carts to be hauled away or for handling in like manner the coal stored.

I carry out these objects by providing a mast or tower to which is connected the 30 usual trolley boom, the mast being also provided with an auxiliary delivery boom carrying a conveyer whereby the coal as fast as it is dug may be carried radially out from the mast and either dumped on a 35 pile to be stored or discharged into cars or other suitable receptacles to be carried way.

My invention may best be understood by reference to the accompanying drawing in which is shown several forms in which my 40 invention may be embodied.

Referring to the drawing:—

Figure 1 represents a general elevation of my apparatus on a small scale showing the manner in which the coal is handled and 5 piled.

Fig. 2 is a plan of the mechanism for rotating the delivery boom.

Fig. 3 is a part elevation and part section taken on the line $\alpha-\alpha$ of Fig. 2.

Fig. 4 is a section taken on the lower line $\alpha-\alpha$ of Fig. 3.

Fig. 5 is a part elevation and part section of an alternate arrangement for stepping the mast, and

Fig. 6 is an elevation showing means for

supporting the tower so that it may be moved bodily.

In the drawings like reference letters indicate like parts.

Referring to Fig. 1 for the general features of the apparatus, A is the mast or tower, B the trolley boom, C the trolley, D the grab or bucket and E is a hopper into which the coal is discharged from the bucket D. These parts may be of any well known construction. Pivoted to the mast or adjacent thereto is an auxiliary delivery boom carrying a conveyer by which the coal is received from the hopper and carried outwardly and dumped.

As here shown the delivery boom F is pivoted to the base of the mast and it is provided with a conveyer belt G. The hopper E is located at the base of the mast in such a position and it is so constructed that it will discharge coal onto the conveyer in whatever position the boom F may be.

Referring to Fig. 1 and to Figs. 2, 3 and 4 wherein the apparatus is shown more in detail the mast is pivoted in a step α supported on a pier α' . The lower portion of the mast is in the form of a hollow cylindrical hub α^2 to the upper end of which is secured the conical base e of the hopper E. The body of the mast is formed of a frame 80 or tower A and this is supported by the hopper base e . The hopper proper is fitted into the base e and is in such a position that the bucket can readily discharge its load 85 into it.

The delivery boom is pivoted at its inner end in such a manner that it may swing laterally whereby an annular heap of coal 90 may be formed.

As herein shown the boom is made up 95 of two parallel stringers $f-f$ united by suitable cross pieces which support the conveyer belt G. The inner ends of the stringers extend on each side of the cylindrical hub α^2 and cross ties $f'-f'$ unite with the stringers 100 to form a frame embracing the hub α^2 . Plates f^2-f^2 are secured to the top and bottom of the frame, an opening being formed in each plate to let the hub α^2 pass through. Anti-friction rolls f^3 are journaled in the 105 plates and these rolls contact with the hub α^2 forming an anti-friction bearing by which the boom is enabled to turn easily on the mast.

Means are provided by which the contents 110

of the hopper may be discharged at a plurality of points according to the radial position of the delivery boom. For this purpose I provide the conical base e with a series of ports e' and a conical sleeve e^2 which fits over the base and is capable of rotating thereon. The sleeve is provided with a delivery spout e^3 connected with an opening in the sleeve which is adapted to register with one or the other of the ports e' as the spout and sleeve are turned.

The conveyer belt G receives the coal and conveys it along the boom to any desired point where it may be discharged by suitable means. In Fig. 2 I have shown a simple mechanism for discharging the coal over the side of the belt. This consists of a plow g secured to the boom at the proper point and resting on the belt. The coal is thrown over each edge of the belt. The position of the plow may be changed as desired so that the entire space to be filled with coal may be covered.

Means are provided for rotating the mast and also for rotating the delivery boom with relation to the mast.

As here shown, I secure to the pier a gear h and this gear is engaged by a pinion h' secured on the lower end of a vertical shaft h^2 journaled in the framework of the boom F . The shaft h' has on its upper end a miter gear h^3 engaging a miter gear h^4 on a shaft h^5 . An electric motor i drives a worm gear i' on a counter-shaft on which shaft there is a pinion i^2 engaging a gear i^3 on the shaft h^5 .

Thus the motor drives the vertical shaft h^2 and its pinion and the delivery boom is turned laterally into any desired position with respect to the mast. The driving mechanism just described is supported on cross beams carried by the delivery boom and travels with it. A brace e^4 connects the boom with the spout e^3 so that as the boom swings the spout and the sleeve e^2 swing with it. The mast is turned in the same manner as the boom by a vertical shaft j having at its lower end a pinion j' engaging the gear h . The shaft j is journaled in brackets j^2 j^3 projecting out from the mast and mechanism similar to that described may be provided to turn the shaft j for rotating the mast.

In Fig. 1 I have shown my apparatus as erected on or near a wharf and located to discharge coal from a barge or vessel V . In operation the grab D is lowered into the barge, filled and drawn in and discharged in the hopper in the usual manner of operating such coal hoisting apparatus.

From the hopper the coal is deposited on the conveyer belt, carried out on the boom and discharged at some point on the heap.

When it is desired to take coal from the heap to be loaded into cars or other means

for removing it, the process is reversed, that is, the coal is dug from the heap with the grab, deposited in the hopper, carried outwardly and discharged from the conveyer into the cars.

If it is desired to load directly from the barge into cars the operation will be the same as that first described except that the conveyer will discharge into the cars instead of discharging onto the heap.

The action of the apparatus is rapid as the conveyer will take care of the coal as fast as it can be dug by the grab.

My apparatus may thus be used for the ordinary work of discharging barges, etc. into cars or into a storage heap, it is relatively cheap in its construction as it may be made to cover a large area and store a large quantity of coal.

It will be understood that the delivery boom may be set at an inclination as shown so that the conveyer belt has to run on an upward grade or it may be set level and the pier raised high enough to extend over the heap when the latter is at sufficient height.

It is further to be understood that any form of conveyer may be used on the boom F , it being immaterial whether one form or another be used so long as the coal is carried away from the hopper as fast as received.

In Fig. 6 I have shown a form of mast or rotatable tower which is built large enough to require no guys and which is supported on a track and capable of being moved bodily from point to point. Referring to Fig. 6, the tower A^2 is supported on rollers o which are disposed on the top of the base p . The base p is carried on trucks p' which travel on tracks p^2 . A counter-weight q balances the delivery boom and a similar counter-weight is provided on the inner end of the trolley boom. This form of tower gives a much greater range of operation to the apparatus than the forms shown in the other figures of the drawing.

It is evident that the mast may be built in the form of an ordinary mast or in the form of a tower as shown in Fig. 6, the essential thing being that it shall be rotatable.

Power may be applied to turn the mast and the boom and to operate the conveyer in any suitable manner, this being a matter of expediency and forming no part of my invention.

In the form of apparatus shown in Figs. 1-4 there is a limit to the arc through which the boom can swing because the delivery boom being of considerable width will come in contact with the shaft j . In order to extend the potential motion of the delivering boom I may provide means for swinging the mast entirely independent of

the means used to swing the boom. In Fig. 5 I show such an arrangement in which the mast A' extends down through the fixed gear h being supported in a step m . A gear m' is secured to the mast below the gear h and the gear m' is engaged by a pinion m^2 secured on a vertical shaft m^3 having thereon a gear m^4 connected with a suitable motor. The boom is swung by means of a shaft u' and a pinion u which latter engages the fixed gear h . By this arrangement the swinging mechanism of the mast does not interfere in any way with the swinging mechanism of the boom and the latter may be swung in either direction until its supporting guys come against the trolley boom.

I claim:—

1. In a hoisting apparatus, the combination of a base, a mast pivoted directly thereto, a boom pivoted to said mast having a conveyer, said boom being pivoted to swing horizontally, a second boom mounted on the mast above the first mentioned boom and adapted to swing horizontally with the rotation of the mast and means on said boom for conveying material to said first-mentioned conveyer.
2. In an apparatus of the character described, the combination of a mast, a boom embracing said mast and arranged to rotate thereon, a stationary gear adjacent to the foot of said mast, and a pinion carried by said boom engaging said gear, a rotating gear on the lower end of said mast below said stationary gear and means for operating said rotating gear to turn the mast.

3. In an apparatus of the character described, a base, a mast including a hopper rigidly connected thereto and journaled on the base, the hopper having ports therein, a boom pivoted on the mast below the hopper and a spout rotatably mounted on the hopper to register interchangeably with the ports of the hopper to discharge material from the hopper.

4. In an apparatus of the character described, the combination of a mast, a boom pivoted on the foot of the mast, a conveyer on said boom, a hopper on said mast having ports therein, a sleeve surrounding said hopper and arranged to rotate thereon and a discharge spout connected with said sleeve and adapted to register with one or the other of said ports to discharge material onto said conveyer.

5. In an apparatus of the character described, including a pivoted mast having a cylindrical hub at its lower end, a hopper having a conical base secured to the upper end of said hub, said base having a plurality of ports, a conical sleeve fitting outside of said base and rotatable thereon, said sleeve having an opening adapted to register with said ports, a discharge spout connected with said opening and a conveyer operating with said spout to receive the contents of the hopper.

In testimony whereof I have affixed my signature, in presence of two witnesses.

JAMES B. PHILLIPS.
